(Continued)*Primary Examiner* — Karen S Acker(57) **CLAIM**

The ornamental design for a comforter, as shown and described.

DESCRIPTION

FIG. 1 is a front-top perspective view of a comforter showing my new design;

FIG. 2 is a front-bottom perspective view thereof;

FIG. 3 is a rear-top perspective view thereof;

FIG. 4 is a rear-bottom perspective view thereof;

FIG. 5 is a front elevational view thereof;

FIG. 6 is a rear elevational view thereof;

FIG. 7 is a left elevational view thereof;

FIG. 8 is a right elevational view thereof;

FIG. 9 is a top plan view thereof; and,

FIG. 10 is a bottom plan view thereof.

The evenly spaced broken lines and areas within them depict environmental subject matter that forms no part of the claimed design.

The dot dash broken lines depict claimed feature lines intended to indicate how the comforter is to be folded.

1 Claim, 10 Drawing Sheets---
